(57) **CLAIM**

The ornamental design for a computer interface device, as shown and described.

DESCRIPTION

FIG. 1 is a right side view of a computer interface device showing my new design;

FIG. 2 is a bottom view thereof;

FIG. 3 is a front left view thereof;

FIG. 4 is a front right view thereof;

FIG. 5 is a left side view thereof;

FIG. 6 is a top view thereof;

FIG. 7 is a front view thereof;

FIG. 8 is a rear left view thereof; and,

FIG. 9 is a rear right view thereof.

The broken line portion of the figure drawings is included to show unclaimed subject matter only and forms no part of the claimed design.

1 Claim, 9 Drawing Sheets
